UNITED STATES PATENT OFFICE.

MARGARET M. MAXWELL, OF BRIDGEPORT, CONNECTICUT.

GARMENT CLASP.

1,403,907.

Specification of Letters Patent. Patented Jan. 17, 1922.

Application filed April 21, 1921. Serial No. 463,224.

To all whom it may concern:

Be it known that I, MARGARET M. MAXWELL, a citizen of the United States, residing at Bridgeport, county of Fairfield, State 5 of Connecticut, have invented an Improvement in Garment Clasps, of which the following is a specification.

This invention relates to garment supporters and has for its object to dispense 10 with independent shoulder straps on various articles of ladies' wear, as for instance, chemise, vest, brassiere, and evening dress. It consists principally of a clasp or buckle adapted to secure itself by a single movement, both to the strap passing over the shoulder and to one or several garments to be supported.

Fig. 1 is a perspective view illustrating 20 the use of the clasp;

Fig. 2, a side elevation showing the clasp with the parts in operative position;

Fig. 3, a rear elevation illustrating the manner of threading the strap through the 25 passages in the back of the clasp;

Fig. 4, a longitudinal section of the buckle or clasp showing the parts in the inoperative or released position;

Fig. 5, a similar sectional view showing the parts in operative or locked position and 30 illustrating the grip on the strap and the garment; and

Fig. 6 is a sectional view showing the 35 lever in a partly closed position and the tongue in engagement with the garment to be held.

The body of the buckle or clasp is a box-like structure, consisting of a back portion 1 having parallel sides 2, and an end 3. The back is provided with two transverse 40 slots 4, and there is a single slot 5 in the end adjacent to the back. Pivoted to the back by means of a pintle 6, or other suitable means, is a bent lever 7 of ordinary construction, having a short arm 8 provided 45 with teeth 9 at its free end and adapted to bite into and grip a strap in the usual and well understood manner. The long arm 10 of this lever serves as a finger piece to facilitate the operation of the buckle or 50 clasp.

The particularly novel feature of this device is the tongue 11 carried by the lever and serving to fasten the clasp to an additional article or articles at the same time 55 and by the same movement that causes the teeth to grip the strap 12, see Figures 5 and

6. This tongue may be pivoted to the lever by the pintle 13 passing through the ears 14, as shown, or it may be mounted in any other manner that may be expedient. The 60 details are unessential so long as movement of the arm to close the clasp on a strap will force the free end of the tongue into binding engagement with a garment or garments to be supported. As shown, the end of the 65 tongue passes through the slot 5 and carries with it a portion of the fabric, but the slot is not necessary as a very satisfactory fastening may be had by substituting a depression in the end or the back for the slot, and 70 in some cases the mere pressure of the tongue against the end or back is sufficient.

In use, the shoulder strap is threaded between the short arm of the lever and the upper end of the back 1, as shown in Figure 75 5, then downwardly and to the right, through the upper slot 4, then down again and to the left, through the lower slot 4, and finally out through the slot 5 in the end. This arrangement causes the strap to lie close to 80 the back portion of the body out of the way, and the portion of the strap lying in slot 5 assists the tongue in making the garment fast. With the arm 10 in raised position, the clasp may be slid along the strap to the 85 desired height, the edges of the garments to be supported are laid on the body of the clasp well above the end, the tongue is pressed down against the fabric and the long arm of the lever is forced down to locking 90 position, simultaneously securing the clasp to the strap and the garments to the clasp. I regard this double fastening by a single movement of the lever as broadly 95 new and desire to secure commensurate protection.

The device can be used in pairs or in sets of four and it may support undergarments alone or an outer garment alone, or, both at the same time. For example: it may support a vest, bandeau, or camisole, or, all of them and an evening gown. The strap may be changed to suit the occasion in color or material and the clasp or buckle will serve for all occasions. The device can be made 105 of any suitable material and ornamented as desired.

Having thus described my invention, I claim:

1. In a device of the class described, a box-like body including a back having a plurality of transverse slots therein, two sides, and an

- end having a slot adjacent to the back, a bent lever pivoted to the sides and having a long and a short arm, the short arm being equipped with teeth adapted to grip a strap or the like when the long arm is substantially parallel to the body, a tongue pivoted to the lever and adapted to pass through the slot in the end when the long arm is moved to cause the short arm to engage a strap or 10 the like.
2. In a device of the class described, a body consisting of a plate having a plurality of transverse slots therein, two side pieces at right angles to said plate and an end piece having a slot adjacent to the plate, a strap lying between the side pieces and passing through said slots, a bent lever having arms of unequal length pivoted between the side pieces, the short arm having teeth 20 adapted to bite into the strap when the long arm is substantially parallel with the plate, a tongue pivoted to the lever and adapted to pass through the slot in the end when the lever is moved to grip the strap, whereby 25 the strap and garment to be supported may be secured to the plate by a single movement of the bent lever.
3. In a device of the class described, a body and a bent lever hinged together and 30 adapted to grip a material to be secured, said body having a slot therein, and a tongue hinged to said lever and adapted to enter said slot when the lever and body are moved to gripping position.
- 35 4. In a device of the class described, a body having a slot therein, a bent lever pivoted to the body, and a tongue pivoted on the lever and adapted to secure a fabric to the body by forcing a portion thereof into 40 said slot.
- 45 5. In a device of the class described, a body, a bent lever pivoted to the body and adapted to bind a strap or the like to the body, and a tongue pivoted to the lever and adapted to secure an additional article to the body.

6. In a device of the class described, a body having a projection thereon, a bent lever pivoted to the body and provided with means for binding a strap thereto, and a 50 tongue carried by the lever and adapted to secure an article by pressing it against said projection.

7. In a device of the character described, a body, a bent lever pivoted thereto and 55 adapted, when in position, to bind a strap or the like against the body, and a pivoted tongue carried by the lever and adapted to secure an additional article to the body.

8. In a device of the class described, a 60 body, a bent lever pivoted thereon and adapted to bind a strap or the like against one portion of the body, and a pivoted tongue carried by the lever and adapted to bind an additional article to another part 65 of the body.

9. In a device of the class described, a body having a slot therein, a lever pivoted to the body and a tongue carried by the lever and adapted to secure an article by 70 pressing it into said slot.

10. In a device of the class described, a body, a lever pivoted to the body and provided with means for securing a strap or the like to the body, and a tongue pivoted 75 to the lever and adapted to secure an additional article to the body.

11. In a device of the class described, a body provided with a laterally extending projection adjacent one end, a lever pivoted 80 to the body adjacent the other end, and a tongue pivoted to the lever and adapted to secure articles to the body by pressing the same against said projection, said lever when in clamping position extending over 85 said tongue and the edge of said projection to provide a cover for the article securing means and the portion of the article secured thereby.

In testimony whereof I affix my signature.

MARGARET M. MAXWELL
